Albert C. Randall, of Providence, R. I.
Letters Patent No. 1057. Dated Oct. 19, 1858.

The schedule referred to in these Letters Patent and making part of the same.

To all whom it may concern:

Be it known that I, Albert C. Randall, of the City and County of Providence, and State of Rhode Island, have invented or produced a new and Ornamental Design for Lockets usually worn to decorate the person, and I do hereby declare that the following is a full, clear and exact description of the same; reference being had to the annexed drawings making part of this specification.

This design consists in embellishing the sides A. A' of miniature valise formed lockets or charms for containing hair, likenesses and other souvenirs, with clusters of flowers or foliage D, at their centers, and alto-relievo bands E, and nail heads at their ends, in such a manner as to give an ornamental finish and appearance to the same. The configuration D, at the center consists of a stem, from which branches in curved lines a series of smaller stems, on which are formed flowers and other foliage of a corresponding ornamental character, and the corners of the spaces be-between the alto-relievo bands E, and nail heads are adorned and relieved from their sameness by smaller configurations or chasings of flowers, similar to those situated in the center, and the sides of the locket or charm are thus made to present a simple, chaste and highly ornamental appearance, in keeping with the objects for which the locket or charm is designed.

What I claim as new and desire to secure by Letters Patent, is.

Embellishing the sides of the lockets or charms for containing hair, like ruffles, or other souvenirs or objects, with clusters of flowers and other configurations as described and represented.

Witnessed.
